The ornamental design for a “lattice panel with diamond pattern and hexagonal transitions,” as shown and described.

DESCRIPTION

FIG. 1 is a front elevation view of a lattice panel with diamond pattern and hexagonal transitions showing my new design;

FIG. 2 is a left side view, which is the same as the right side view, of the lattice panel with diamond pattern and hexagonal transitions;

FIG. 3 is a top view, which is the same as the bottom view, of the lattice panel with diamond pattern and hexagonal transitions; and,

FIG. 4 is a rear elevation view.
